UNITED STATES PATENT OFFICE.

CLYDE E. W. GARDNER, OF DETROIT, MICHIGAN, ASSIGNEE, BY MESNE ASSIGNMENTS,
TO BURROUGHS ADDING MACHINE COMPANY, OF DETROIT, MICHIGAN, A CORPO-
RATION OF MICHIGAN.

MOTOR-STAND FOR ADDING-MACHINES.

1,080,548.

Specification of Letters Patent.

Patented Dec. 9, 1913.

Application filed November 12, 1908. Serial No. 527,786.

To all whom it may concern:

Be it known that I, CLYDE E. W. GARDNER, a citizen of the United States, and resident of Detroit, in the county of Wayne and State of Michigan, have invented certain new and useful Improvements in Motor-Stands for Adding-Machines, of which the following is a specification.

My invention relates to adding machines and more particularly to means for supporting such machines and the motors and connections for operating them.

One of its principal features consists in combining with a simple stand adapted to support the adding machine, a removable platform or support carrying a motor, and operating connections, the parts being so constructed that when the platform and machine are placed in proper position they are in operative relation without the necessity of making positive connection between the parts.

Another feature consists in means for avoiding waste of power in driving the motor.

Other features will be apparent from the following description taken in connection with the accompanying drawings.

In the drawings, Figure 1 is a side elevation of the upper part of the stand showing the platform and adding machine in position; Fig. 2 is a perspective view of the top of the stand having the platform in position; Fig. 3 is a plan view of the motor clutch and bracket; Fig. 4 is a cross section on the line 4—4 Fig. 3; and Fig. 5 is a detail perspective view of the pawl used in the clutch mechanism.

The stand is of any suitable form and construction preferably of metal, and as shown includes the vertical tubular legs 1, the cross bars 21, 22, and the side shelf 23. The adding machine is removably supported by the cross bars 21, 22, the downwardly extending lugs 2 of the frame B of the adding machine resting in sockets 24 on the cross bars. A platform A preferably of cast metal is also removably supported by the cross bars 21, 22. It will be observed that the end of this platform which rests upon bar 21 extends almost the entire width of the

stand and thus has two separated points of support upon the cross bar. The other end of the platform is so shaped that there is a single point of support 25 near the center of bar 22, and it will be obvious that the use of three points of support only insures a firm and proper setting of the platform on the stand without machining the parts. The openings 26 in the platform above the bar 21 are merely for the purpose of permitting the supporting lugs 2 of the adding machine to pass freely through the platform and rest in the sockets 24 on the bar 21. The pins 27 on the platform A are adapted to fit in sockets in frame B of the adding machine so as to insure placing that machine and platform in proper relation to each other for reasons hereafter explained. The platform does not in any sense support the machine, but is a separate and distinct element supported by the frame and adapted to carry a motor for operating the machine and the machine may be placed upon the stand either with or without the platform.

From the platform A there is supported a motor M of any suitable construction and capable of being driven from any desired source of power. As shown there is illustrated in outline an electric motor having a driving shaft M' which is capable of rotation so long as power is transmitted to the motor, and a driven shaft 3, with means for connecting the said latter shaft operatively with the adding machine. These connections may be of any desired character, but as shown the driven shaft has a crank-arm 4, to which is jointed one end of a chain 5, the opposite end of which is connected adjustably with an arm 6, the hub of which is recessed so as to be applied readily to the end of the operating rock-shaft 7 of the adding machine, the arm and shaft having bearing faces that insure the rocking of the shaft with the arm, while permitting the latter to be applied and slipped from the shaft without any positive connections.

It is desirable, when the adding machine is to be operated to accumulate or print an item, to rock the operating shaft first in one direction and then in the other, and to then automatically arrest the shaft, for reasons

well known in connection with the operations of such machines, and I effect this by providing a clutch device of suitable character between the driving shaft and the driven shaft of the motor, said clutch being carried by a bracket A' secured to the support A. Such clutch connections may be of different forms and arrangements to secure the desired result, but as shown the 10 clutch device consists of a pawl 8 pivoted to a disk fast upon the driven shaft and adapted to engage the teeth of a ratchet wheel 9 that is carried by a sprocket 29 which is loosely mounted upon the driven shaft 3 and 15 connected by a chain 30 with a sprocket on the constantly rotating driving shaft, a spring 10, connected to the pawl and to the carrying disk, tending to hold the pawl in engagement with the ratchet. To the 20 bracket is pivoted an arm 12, the lower end of which is in position to engage a lug 13 on the pawl as the latter is carried toward the end of said arm by the rotation of the disk, and the pawl will be thereby swung 25 away from the ratchet against the tension of the spring 10, the crank 4 and arm 6 then being in the arrested position shown in the drawing. By shifting the arm 12 to carry its lower end from the lug 13 the pawl is 30 released, when its spring 10 will carry it into engagement with the teeth of the ratchet, and the driven shaft will be turned in the direction of its arrow by the driving shaft. A spring 18 having its ends attached 35 to the arm 12 and bracket A' acts constantly to maintain the arm 12 in the position shown in the drawings, that is in the path of rotation of the lug 13 and unless said arm is prevented from returning to such normal position 40 during a revolution of the driven shaft it will be seen that when a complete rotation of the driven shaft is effected the lug 13 will be brought against the end of the arm 12, and the pawl will be swung away from 45 the ratchet wheel, and the further rotation of the driven shaft will thus cease after effecting a complete rocking movement of the operating shaft of the machine. I have 50 illustrated and described this form of clutch and connection with the motor merely as one means of carrying out my invention. Any other suitable means for effecting the same result may be employed.

It is extremely desirable to avoid the necessity of making any positive connections between the parts of the adding machine and the control devices of the motor as such connections will result in loss of time and cannot frequently be made by those who are 55 in charge of such machines, and almost invariably involve detachable parts which may be lost and interfere with the desired operations. I therefore provide means whereby a machine is placed in a defined 60 position with relation to the support A and

operative connections, and then there will be parts in position to effect the desired control of the motor from the machine without the necessity of making any connections or adjustments. Such parts may be differently 70 arranged and constructed, but as shown there is a contact device in the form of a stud C which is upon a shifting blade 15, connected at one end with the upper end of the arm 12, and this contact device or 75 stud is in such position as to coat with a contact device D of the machine so that upon moving the latter contact device the contact device C and blade 15 will be shifted and shift the arm 12 to carry it from the 80 path of the lug 13 on the clutch pawl.

As shown the contact device D is a bell-crank lever swung in one direction by a spring 16 and in the other by a pawl 17, pivoted to the starting arm E of the machine, so that when the starting arm is depressed the pawl is swung, the contact C and blade 15 are shifted to shift the arm 12, and the machine is started, the spring 16 swinging the contact device D away from 90 the contact device C, when pressure on the starting arm is released, and the spring 18, connected with the arm 12, restoring the latter to normal position.

It is of course undesirable to transmit 95 the power constantly to the motor, and to avoid the waste of power that would result from running the motor when there is no machine in position to be operated, or when it is not in operation, the energizing current 100 may, as shown, be conducted to the motor by suitable cables or conductors leading to and from a switch box X, containing a suitable switch, controlled by a push button α , to break the circuit whenever desired. I 105 however provide means whereby the switch or other control device may be automatically shifted so as to arrest the transmission of power to the motor whenever the devices D, C are not in contact. To this end the 110 blade 15 may be connected to operate the switch 20, which, as shown, projects through the top of the switch box X into position to be engaged by said blade and is carried to a position to break the circuit by the action 115 of the spring 18 when the parts D, C are not in contact, but is shifted in position to make the circuit as soon as the contact device D has moved the device C and its connections to a position to release the clutch 120 pawl 8.

Any suitable form of switch mechanism may be employed. In the conventional illustration of such devices in Fig. 1, the switch 20 is shown as a simple lever, suitably 125 fulcrumed on a bracket 20^a within the box X and normally held in the position shown by a spring 20^b. Said switch lever is connected by a conductor 20^c with one pole of the battery, the other pole of which is con- 130

nected, as by a conductor M^2 , with the motor. The latter is, by a conductor M^3 , connected with a second contact or switch member in the box X. As shown, this second contact comprises a spring arm 50 of conducting material to which the conductor M^3 is electrically connected and a member 50^a mounted in a bracket and having its lower end normally making electrical contact with the member 50, while its upper end projects into the path of the switch lever 20. The stem of the push-button 20 extends through the bracket carrying the member 50^a of the second contact and rests upon the spring member 50 so that by depressing said button the members 50, 50^a can be separated to break the circuit at any time, as above described.

By connecting the crank shaft of the motor with the arm which is connected to the operating shaft of the machine by means of a flexible connection, as the chain 5, a positive movement is imparted to the said arm from the motor when the arm is swung in one direction, that is the direction corresponding to the forward stroke of the machine where the motion should be positive, but the connection 5 can be relaxed on the return movement so that if the parts of the machine are not carried on their return movement as rapidly as the shaft on the motor rotates the connection 5 can slacken without interfering in any way with the slower action of the machine.

From the above description it will be observed that a special feature of my invention resides in making the parts as detachable units which may be brought together in operative relations with great ease and accuracy. There are four such units, the adding machine, the platform, the motor and the stand. The motor must be positively connected to the platform by screws 157 engaging lugs on the motor casing, and the motor must be positively connected to the machine by securing chain 5 to operate shaft 7, but all other operative connections are made by simply placing the units in position. The centering pins 27 insure placing platform A in such position on the bars 21, 22 that the operating connections will be in proper relations and those pins will prevent accidental movement of the platform out of position. By this means the stand frame is equally adapted without change for hand or power machines, and the latter may be applied and held without bolts or fastenings. If a hand machine is purchased no change is required in the stand to apply power, it being simply necessary to apply the platform motor to the frame. So also if a power machine is used, temporarily or otherwise, for hand operations the frame need not be changed, but the motor and platform may be removed and the

machine used with the frame alone. If any change in this motor is required it may be readily unbolted from the platform and replaced, the arm 6 being disconnected from its rock-shaft; this also permitting the instant removal of the machine from its supports.

Without limiting myself to the construction and arrangement shown, I claim:

1. The combination with an adding machine, including an operating shaft, of a stand adapted to support said machine, a motor supported by the stand and having driving devices and a rotatable driven shaft, means for connecting said driven shaft operatively with the operating shaft of the adding machine, a shiftable device controlling connection of the driven shaft of the motor with the driving devices thereof, and means including a contact member on the adding machine for actuating said shiftable device.

2. The combination of a stand adapted to support a detachable adding machine, a motor, a driving member connected with the motor to be constantly rotated thereby, a driven member adapted to be connected with the actuating member of an adding machine supported by the stand, and means for connecting and disconnecting said driving and driven members, including a contact device arranged to coact with and be shifted by a contact device on the adding machine mounted on the stand.

3. The combination of a stand adapted to support a detachable adding machine, a motor having a rotatable driving shaft, a driven shaft, means for connecting the latter shaft with the actuating member of an adding machine supported by the stand, and means for connecting said shafts and automatically disconnecting them at the termination of a rotation of the driven shaft including a shiftable member and an operating contact device arranged to coact with and be actuated by a contact device on the adding machine mounted on the stand.

4. The combination of a stand having a support for a detachable adding machine, a motor supported by the stand, a control device controlling the transmission of power to the motor, a shiftable contact device connected to operate the control device and in position to coact with a contact device on the machine to be shifted by the movement of the latter device.

5. The combination of a stand having a support for a detachable adding machine, a motor supported by the stand, a control device controlling the transmission of power to the motor, a shiftable contact device connected to operate the control device and in position to coact with a contact device on the machine to be shifted by the movement of the latter device, means for operating the machine from the motor, and devices con-

- nected with the shiftable contact device whereby to put said last named means into and out of connection with the motor by the adjustment of said shiftable contact device.
6. The combination of a stand having a support for a detachable adding machine, and supporting a motor having a driving shaft, a driven shaft, a clutch for connecting said shafts, means for engaging the parts of the clutch and for disengaging them automatically at the completion of each rotation of the driven shaft, devices for connecting the driven shaft operatively with the actuating member of an adding machine supported by the stand, and a shiftable contact device and connections whereby to control the operations of the clutch, said contact device being in position to coact with a contact device of an adding machine mounted on the stand to be shifted therefrom.
7. The combination of a stand having a support for a detachable adding machine, and supporting a motor having a driving shaft and a driven shaft and an intermediate clutch, means for engaging the parts of the clutch and for disengaging them automatically at the completion of each rotation of the driven shaft, devices for connecting the driven shaft operatively with the machine, a shiftable contact device and connections whereby to control the operations of the clutch, said contact device in position to coact with a contact device of the machine to be shifted therefrom, and a control device controlling the transmission of power to the motor, said control device connected to be shifted on the movement of the said shiftable contact device.
8. The combination with a stand having a support for a detachable adding machine, and an electric motor with a driving shaft and driven shaft and clutch device intermediate the two shafts, of means for operating the clutch to arrest the driven shaft at the completion of each rotation, means for connecting the driven shaft operatively with the adding machine, a switch controlling the transmission of current to the motor, and means for shifting the switch and the clutch, said means provided with a contact in position to be shifted by a contact device on the machine.
9. The combination with the motor of an adding machine and with means for transmitting power thereto and with a controlling device therefor, of a driving shaft, a driven shaft, means for connecting and disconnecting the two shafts, and means for automatically shifting the latter means to disconnect the driven shaft from the driver at the end of each rotation of the driven shaft.
10. A stand for an adding machine provided with a support carrying a motor, stopping and starting means including a contact device, the said support being provided with means for defining and limiting the position of the machine on said stand with reference to the contact device.
11. A stand for adding machines consisting of a frame adapted to support an adding machine thereon, and a platform detachable from the frame, and means for connecting a motor thereto.
12. The combination of a frame provided with bearings for an adding machine, a platform, and means for supporting it detachably on the frame independent of the machine, and means for connecting a motor to said platform.
13. The combination of a frame provided with bearings for an adding machine, a platform and means for supporting it detachably on the frame independent of the machine, and a motor connected detachably to said platform.
14. The combination of a frame provided with bearings for an adding machine, a platform and means for supporting it detachably on the frame independent of the machine, a motor, and means for hanging it from the platform.
15. The combination with a stand adapted to support an adding machine, of a removable platform carrying a motor and adapted to rest on said stand below said adding machine.
16. The combination with a stand, of an adding machine having depending supporting lugs adapted to rest on said stand, and a removable platform carrying a motor adapted to rest on said stand below said adding machine.
17. The combination with a stand, of an adding machine having depending supporting lugs adapted to rest on said stand, and a removable platform carrying a motor adapted to rest on said stand below said adding machine, the said platform being provided with openings through which said lugs pass.
18. The combination with a stand, of an adding machine having depending supporting lugs adapted to rest on said stand, a removable platform carrying a motor adapted to rest freely on said stand below said adding machine, and means on said machine and platform for maintaining the platform in proper position with relation to the machine.
19. The combination with a stand, of an adding machine resting thereon, and a platform carrying a motor resting freely on said stand below said adding machine, the said platform and machine being provided with interengaging elements to center the platform.
20. The combination with a stand having cross bars adapted to support an adding machine.

chine, of a platform carrying a motor and adapted to rest on said cross bars at three points below said adding machine.

21. The combination with a stand adapted to support an adding machine, of a platform carrying a motor and switch adapted to rest on said stand below and independently of said adding machine, and centering

pins on said platform adapted to engage said machine.

In testimony whereof I affix my signature in presence of two witnesses.
